John G. Perry.

UNITED STATES PATENT OFFICE.

JOHN G. PERRY, OF SOUTH KINGSTON, RHODE ISLAND.

SAUSAGE-FILLER.

Specification of Letters Patent No. 28,900, dated June 26, 1860.

To all whom it may concern:

Be it known that I, JOHN G. PERRY, of South Kingston, in the county of Washington, in the State of Rhode Island, have 5 invented a new and Improved Machine for Filling Sausages; and I do hereby declare that the following is a full and correct description thereof, reference being had to the accompanying drawings and to letters of 10 reference marked thereon, similar letters in the different figures denoting the same parts.

In these drawings, Figure 1 is a perspective view of the machine. Fig. 2 is a perspective view of the same open to show the 15 inside. Fig. 3 is a view of the cylinder. Fig. 4 shows one of the stud-slips that goes in the cylinder.

This machine consists of a case A divided into an upper and lower part, and a cylinder 20 B lying lengthwise in it, and turning in bearings in the ends of the case; these bearings are placed to one side of the center of the cavity of the case, so as to bring the cylinder close to one side of the cavity of the 25 said case. The cylinder B has a spiral slot C made through it extending nearly from one end to the other, of the cylinder. This spiral slot is filled with the stud-slips D (See Fig. 4) put in endwise, and across the 30 axis of the cylinder. The stud-slips are made long enough to just reach across the cavity of the case at its shortest diameter for this cavity should not be made exactly 35 round, but should be of an oval, or approaching a heart shape, so that a line of

a certain length extending through and across the axis of the cylinder in any direction in the plane of its motion, will just reach from one side of the cavity to the other. The stud-slips are made to slide easily through the 40 slot in the cylinder, so that when it is turned they will be pushed in on one side and out upon the other, by their ends coming in contact with the side of the cylinder. On the top of the case and near one end is placed the 45 hopper E to receive the meat and an opening F is made at the other end to discharge the meat; a tube or nozzle G is put into this opening to receive the cases to be filled.

The operation of the machine is as follows: Motion being given to the cylinder with one hand by means of the crank, H, the meat is fed into the hopper E by the other and is drawn into the chamber by the stud-slips D but as it cannot go around with the 55 cylinder because it is set close to one side of the case it is forced by the spiral position of the studs to pass along toward the other end of the chamber and out of the opening F through the nozzle into the cases. 60

Having thus described my machine, what I claim as my invention, and desire to secure by Letters Patent is—

The combination of the cylinder B, and stud-slips D, substantially as described here- 65 in, and for the purposes set forth.

JOHN G. PERRY.
